DESIGN FOR A GOBLET OR SIMILAR ARTICLE

Charles R. Keil, Tiffin, Ohio, assignor to United States Glass Company, Pittsburgh, Pa., a corporation of Pennsylvania

Application March 29, 1935, Serial No. 56,122

Term of patent 7 years

To all whom it may concern:

Be it known that I, Charles R. Keil, a citizen of the United States, residing at Tiffin, in the county of Seneca and State of Ohio, have invented a new, original, and ornamental Design for a Goblet or Similar Article, of which the following is a specification, reference being had to the accompanying drawing, forming part thereof.

The figure is a perspective view of a goblet showing my new design.

The distinctive feature of my new design is the border or banding as shown.

I claim:

The ornamental design for a goblet or similar article, substantially as shown and described.

CHARLES R. KEIL.
